Application July 31, 1942, Serial No. 453,118

41 Claims. (Cl. 66—96)

1

The present invention generally relates to the formation of welt fabrics in flat knitting machines and, more particularly, pertains to mechanism for the setting up of welt bars and welt rods in multi section full-fashioned hosiery knitting machines. This application is a continuation in part of our copending application Serial Number 304,492, filed November 15, 1939, now Patent No. 2,303,412.

In accordance with the usual practice in the manufacture of full-fashioned hosiery, the operator, pursuant to the laying and kinking of the first course of yarn on the several banks of needles of a multi section full-fashioned hosiery knitting machine, must manually bring each welt bar individually into operative relationship with the associated bank of needles and, in so doing, must exercise the greatest degree of care and skill to locate the welt hooks in a particular relation with the knitting instrumentalities, that is, the operator must tediously place each welt bar so that the welt hooks thereof pass between the needles at a point intermediate the spaced superposed rows of sinkers and knockover bits because, otherwise, the hooking of the loops of the first course will be faulty, resulting in the production of bad fabric.

Moreover, following the proper placement of each welt bar, the operator must attach an individual draw-off strap to each welt bar for connecting the latter to the take-up mechanism of the machine. Furthermore, after the knitting of a sufficient length of fabric and prior to the turning of the latter to form the ordinary double ply welt, the operator must manually place a welt rod individually on each fabric being knitted on the several banks of needles of the multi section machine, and attach individual draw-off straps to the opposite end portions of each welt rod.

Since modern full-fashioned hosiery knitting machines average from twenty to thirty sections, it will be appreciated that the number of manual operations required, and the time consumed in the setting up and turning of the welt fabrics according to the usual procedure hereinbefore explained are considerable, and greatly hamper production, all of which necessarily affect the cost of manufacturing and, consequently, increase the price that the purchasing public must pay for the goods.

It is, therefore, the primary object of the invention to provide mechanisms and means whereby the number of manual operations and the time required for the set-up and turning of welts are reduced to a minimum, thus increas-

2

ing production and correspondingly decreasing the manufacturing and purchasing cost.

The invention especially aims to provide mechanisms and means whereby the welt bars may be brought accurately in position with respect to their associated banks of needles without dependence on any particular skill of the operator so that the proper relationship of the welt hooks with the needles, sinkers, and knockover bits is

10 assured.

Among the most important objects of the invention is the provision of mechanisms and means adapted to move all the welt bars simultaneously towards the banks of needles for bringing all 15 the welt hooks in position to engage and tension in unison the loops of the set-up course or courses in the several knitting sections of the machine while eliminating the necessity of separately attaching individual draw-off straps to 20 each of said welt bars.

An equally important object of the invention resides in the provision of mechanisms and means devised to support a welt rod for each knitting section of the machine, and actionable 25 to deposit all the welt rods simultaneously on the lengths of fabrics being knitted in the respective knitting sections to permit the turning of the fabrics for the formation of double ply wefts.

30 It is also an important object of the invention to provide mechanisms and means whereby the welt rods throughout the length of the knitting machine may simultaneously be engaged and drawn against the corresponding fabrics for the 35 formation of the double ply wefts, without requiring the separate manual attachment of individual draw-off straps to opposed end portions of said welt rods.

Other numerous meritorious objects and ad- 40 vantages will be in part obvious and in part pointed out hereinafter.

In order that the invention and its mode of operation may be more readily understood by those skilled in the art, we have, in the accom- 45 panying drawings and in the detailed description based thereupon, set out possible embodiments of the invention.

In these drawings:

Figure 1 is a top plan of a portion of a full- 50 fashioned hosiery knitting machine embodying one form of the invention;

Figure 2 is an end elevation of the same;

Figure 3 is a view similar to Figure 2 illustrating a modified form of the invention;

55 Figure 4 is a broken top plan of the welt bar

supporting structure included in that form of the invention shown in Figures 1 and 2;

Figure 5 is a sectional detail taken on line 5—5 of Figure 4;

Figure 6 is an enlarged sectional detail taken on line 6—6 of Figure 1, with parts removed for the sake of clarity;

Figure 7 is a vertical section looking in the general direction of line 7—7 of Figure 6;

Figure 8 is an enlarged detail of parts of the welt bar supporting structure included in that form of the invention illustrated in Figure 3;

Figure 9 is a vertical section through the length of the rail supporting block shown in elevation in Figure 8;

Figure 10 is a detail looking in the general direction of line 10—10 of Figure 9;

Figure 11 is a sectional detail looking in the general direction of line 11—11 of Figure 10;

Figure 12 is an enlarged cross sectional detail of a portion of the parts shown in Figure 8;

Figure 13 is an enlarged sectional detail of parts shown in Figure 2;

Figure 14 is an enlarged sectional detail of parts shown in Figure 3;

Figure 15 is an enlarged detail of the welt rod holding and positioning device and of the fabric take-up mechanism;

Figure 16 is an enlarged section taken on line 16—16 of Figure 15;

Figure 17 is a section taken on line 17—17 of Figure 16;

Figure 18 is a detail illustrating a constructional feature of a part of the take-up mechanism;

Figure 19 is a top plan of another portion of the take-up mechanism;

Figure 20 is an enlarged perspective of the welt rod holding and positioning mechanism.

Figure 21 is a section on a reduced scale taken on line 21—21 of Figure 16;

Figure 22 is a diagrammatic illustration of certain of the most important features of the invention.

Referring more particularly to the drawings wherein like characters of reference will indicate corresponding parts throughout, the machine frame is designated at 20 and carries the usual bearings for supporting the various shafts of the knitting machine including the main cam shaft 22. The machine frame is also provided with the usual center beam 24 and front table 26. Arranged about the center beam 24 in the customary manner are the multiple knitting sections such as those designated by the reference character 28. Each knitting section 28 comprises a straight needle bar 30 with its bank of needles 32 disposed to cooperate with the presser edge 33, sinkers and dividers 34, and knockover bits 36 for the knitting of fabric in the manner well known in the art. Yarn is fed to the knitting sections 28 by means of yarn carriers 38 connected to the carrier bars 40 supported in brackets 42 of the machine frame 20.

The elements so far described are found in well known knitting machines commonly used in the trade and, since the construction and operation are fully understood by those familiar with the art, an elaborate description thereof may be dispensed with herein.

Adapted to cooperate with the knitting sections 28 are welt bars 44, each provided with a bank of welt hooks 46. The welt hooks 46, which also serve as transfer elements, are adapted for cooperative action with the knitting needles 32 to re-

ceive loops of the initial courses knitted by the banks of needles and subsequently return said loops onto the needles in the formation of double ply welts.

In Figures 1, 2, and 4 to 7 inclusive, there is shown one form of mechanism for supporting the welt bars 44 so that they may simultaneously be moved through manual operation towards the needles 32, and may simultaneously be moved through automatic operation away from the needles 32. According to this form of mechanism, there are provided two carrier devices 48, one for each end of each welt bar. Each carrier device 48 preferably consists of a supporting slidable plate 50 upon which is mounted a vertical split pin 52 adapted for frictional engagement with the wall of a suitable aperture 54 bored through the corresponding end portion 56 of the associated welt bar 44, as more clearly shown in Figure 5.

Suitably fixed in relative spaced relation along the front table 26 of the machine frame are pairs of bearing brackets such as that represented at 58, which brackets support a rotatable shaft 60 extending throughout the length of the knitting machine.

Mounted freely upon the shaft 60 within the confines of each knitting section 28 is a pair of hollow casings 62 preferably of circular configuration and each (as more clearly shown in Figure 7) having a bore 64 suitably formed in the peripheral surface thereof and opening therein.

Received within the bore 64 and rigidly connected thereby by means of a locking screw 66 is one end 68 of an elongated channelled rail 70 disposed so that its intermediate portion extends transversely of the front table 26 and its free end portion projects towards the needle bar 30.

As represented in the drawings, the portion of each rail 70 transversely extending over the front table 26 may be provided with a laterally extending lug 72 carrying a bolt 74 adapted for engagement with said table and thus secure the rail 70 in fixed position relative to the associated needle bar 30. The casings 62 within the confines of each knitting section 28 are located on the shaft 60 so that the free ends of the rails 70 lie in substantially transverse alignment with the opposite extremities of the corresponding needle bar 30. This location of the casings 62 may be fixed by their abutment against the bearing brackets 58.

Associated with each casing 62 and freely engaged on the shaft 60 as will more clearly appear from Figures 6 and 7, is a disc 76 of a size to fit concentrically within the hollow portion of said casing. The inner face of each disc 76 enclosed in the casing 62 is formed with an inner groove 78 and an outer groove 80 interconnected by means of a passage 82 cut on a line tangent to the inner groove through the portion 84 separating said grooves.

A flexible cable 86 preferably in the form of a coil spring is nested within the grooves 78 and 80, one end portion 88 of said cable being retained securely within the inner groove 78 by means of an annular plate 90 suitably fixed to the disc 76, for instance by bolts 92 or like fastening elements.

Arranged adjacent the outer face 94 of each disc 76 and keyed to the shaft 60, as shown at 96, is a clutch member 98 provided with a spring pressed rotatable plunger 100 normally adapted for engagement with an opening 102 cut into said disc 76 whereby rotation of the shaft 60 in the direction of arrow B or in the direction of arrow 75 C will be transmitted to said disc 76 and, ac-

cordingly, wind or unwind the associated flexible spring cables 86. The free end 104 of each flexible cable 86 is introduced into the corresponding channeled rail 70 to slide freely therein and is connected to a plunger 108 rigidly attached by means of pins 108 or like fastening elements to the respective supportable sliding plates 50 of each of the welt bar carrier devices 48.

Because of the provision of the clutch arrangement, it will be understood that the mechanism for advancing and retracting the welt bar carrier devices 48 within the confines of any one of the knitting sections 28 may be rendered inoperative at will.

From the foregoing description, it will be understood that when the clutch members 98 are in active engaged position, rotation of the shaft 60 in the direction of arrow B will cause the welt bars 44 to move away from the needle bars 30, whereas rotation of the shaft 60 in the direction of arrow C will cause the welt bars to move towards the needle bars.

Rotation of the shaft 60 in the direction of arrow B, which is utilized to slide the welt bars 44 away from the needles for drawing the welt fabrics as the knitting of courses progresses, is accomplished by means of a pulley or drum 110 affixed to said shaft, and of a take-up cable 112 mounted thereabout, said cable being maintained in constant pulling tension, for example, by passing in the usual well known manner over an overhead pulley and thence down to a counterweight (not shown).

The welt bars 44 are moved in unison towards the needle bars for the hook-up operation, that is, to bring the welt hooks 46 in position adjacent the needles 32 for engaging the initial sinker loops, by manually rotating the shaft 60 in the direction of arrow C.

For the purpose of assuring the accurate positioning of the welt hooks 46 in relation to the needles 32, and also prevent the tips of the hooks from injury by ramming into parts of the knitting machine, such as the presser edge 33 when moving the welt bars towards the needle bars, there may be provided a limit stop preferably consisting of a one-tooth ratchet wheel 114 affixed to the shaft 60 and adapted to be engaged by a dog 116 conveniently mounted on a suitable portion of the machine frame. This dog may be moved manually by the operator into contact with said wheel 114 as the welt hooks 46 approach the needles 32 so that following rotation of the shaft 60 in the direction of arrow C, the tooth 118 of said wheel 114 will abut the end of the dog and accordingly arrest further movement in that direction.

In Figures 3 and 8 through 12, there is illustrated a modified form of the welt bar movement imparting mechanism. In accordance with this modified form, auxiliary shafts 120 and 122 are provided, said shafts extending longitudinally of the machine and being supported in bearings (such as bearings 124 in Figure 3) spaced along and fixed to the front table 26. The shaft 122 is stationary, whereas the shaft 120 is capable of rocking motion as indicated by the arrows D and E in Figure 3.

Rigidly fixed to the auxiliary rockable shaft 120 are arms 126 preferably spaced so that one arm is located between each pair of knitting sections and at the outside end of each of the end knitting sections. Adapted for pivotal connection to the arms 126 are link devices 128.

Each of the link devices 128 preferably com-

prises an elongated tubular section 130 having one end screw-threaded, as shown at 132 (Figure 12) for adjustably receiving a forked shaped member 134 constructed for slidable engagement with a somewhat reduced portion 136 of a connection element 138, thus guiding said element into the tubular section 130. The forked shaped member 134 may be locked in adjustable position relatively to the tubular section 130 by means of a locking collar 140. It will be appreciated that the reduced portion 136 provides the connection element 138 with shoulders 142 which may contact the adjacent surfaces 144 of the forked shaped member 134 and, therefore, limit the introduction of said element into the tubular section.

The connection element 138 is preferably formed with a key-hole shaped slot 146 adapted for engagement with a stud headed pin 148 carried by the associated arm 126 whereby a detachable pivotal connection may be had between said arm 126 and associated link device 128. Freely received within the other end of the tubular section 130 and arranged in telescoping relationship therewith is a connection piece 150 terminating with an enlarged arcuate finger 152 pivoted, for instance, by means of a riveted pin 154 to a welt bar carrying element 156 on which the corresponding end of the welt bar is detachably mounted. Each element 156 is provided with rollers or pins 158 for the purpose to be hereinafter specified.

The connection piece 150 is normally urged inwardly of the tubular section 130 by means of a coil spring 160 having one of its ends connected to said connection piece 150, as shown at 162 (Figure 8), and the other of its ends connected to the portion 136 of the connection element 138, as shown at 164 (Figure 12). The inward movement of said connection piece 150, however, is limited by means of shoulder 166 formed thereon and adapted to abut the adjacent edge of the tubular section 130, as more clearly appears from Figure 8.

The provision of the spring 160, it will be appreciated, moreover furnishes a yieldable connection between the connection element 138 and the connection piece 150 which affords to the device a resilient and flexible union advantageous in effecting the knitting of the welt fabric, as will be described more fully hereinafter.

It will be noted that the spring 160 also acts to exert a constant pull on the connection element 138, thus normally urging the key-hole shaped slot 146 into positive engagement with its stud headed pin 148, accordingly establishing the proper secured connection between the device and its associate operating arm 126, but that said connection element 138 may be moved in a direction opposite to that of the pull exerted thereon by the spring 160 to bring the key-hole shaped slot 146 in position for disengagement from said pin 148 on the associated arm 126. In this manner, it will be understood that each welt bar carrying assembly consisting of the link devices 128, carrying elements 156, and welt bar 44 of any individual knitting section 28 may be removed easily and readily as a unit from its position on the knitting machine frame without affecting the attachment as to the other knitting sections, whenever such removal is necessary for any purpose such as the adjustment, repair, or replacement of parts.

From the foregoing description of the welt bar carrying assemblies, it will be understood that by

turning the shaft 120 in the direction of arrow D or arrow E, the link devices 128 and welt bars 44 throughout the entire length of the knitting machine will be moved in unison towards or away from the needles 32.

The link devices 128 and the welt bars 44 are guided in their movements towards and away from the needles 32 by means of rails 168 having tracks 170 on which ride the rollers or pins 158 of the welt bar carrying elements 156. The track 170 of each of the rails 168 terminates with a free end portion 172 extended to point in close proximity of the corresponding end of the associated needle bar 30 (Figure 3). Each of the rails 168 is carried by a block 174 rigidly secured to the auxiliary fixed shaft 122.

Since the proper engagement of the welt hooks 46 with the needles 32 depends upon the accurate positioning of the free end portions 172 of the tracks 170 in relation to the needles, the invention contemplates the provision of a highly micrometric adjustable connection between the rails 168 and the supporting blocks 174.

As illustrated in the drawings, particularly Figures 8 to 11 inclusive, such a connection may be had by providing each of the blocks 174 with a transversal recessed portion 176 into which the attaching end portion 178 of the associated rail 168 is fitted loosely for endwise, edgewise, and sidewise adjustments. The end portion 178 of the rail 168 received in the transversal recessed portion 176 of the corresponding supporting block 174 is connected to said block by means of a bolt 180 disposed to project through an elongated aperture 182 formed in the wall of said recessed portion to extend longitudinally thereof.

Arranged in said wall to penetrate into the elongated aperture 182 from the diametrically opposed ends thereof are screw-threaded elements 184 and 186 adapted to bear on opposite sides of said bolt 180 whereby, upon relatively screwing or unscrewing the elements 184 and 186, the rail 168 is slid endwise so that the free end portion 172 of said track 170 is adjusted to a point nearer to, or further away from, the needles 32.

Arranged on each of the blocks 174 to bear upon one edge of the rail end portion 178 is an adjusting element 188 which may be in the form of a spring while also arranged on said block to bear against the opposed edge of said rail is a screw-threaded member 190 whereby, upon screwing or unscrewing said member, the rail 168 is rocked edgewise so that the free end portion 172 of the rail track 170 is adjusted to a higher or lower point in relation to the needles 32.

Likewise arranged in said block to bear upon one side of the rail attaching end portion 178 is a plug 192 associated with a screw-threaded pin 194 whereby upon screwing or unscrewing said pin, the plug 192 displaces the rail sidewise so that the free end portion 172 of the rail track 170 is adjusted to a point to the right or to the left in relation to the needles 32. To permit this sidewise adjustment, the bolt 180 connecting the rail end portion 178 to the block 174 may be associated with a spring washer 196.

Due to this particular mode of connection between the rails 168 and their supporting blocks 174, it will be appreciated that there is provided universal adjusting means whereby the proper and accurate positioning of the welt hooks 46 relative to the needles 32 is assured.

Attention is called to the fact that because of the construction and association of elements, there is provided such a flexibility of adjustments

that not only can the particular welt bar supporting elements in each knitting section be adjusted relatively to each other to assure the proper movement of the welt bar in the associated knitting section, but said elements in one knitting section may be adjusted relatively to such elements in the other knitting section to assure the proper movement of the welt bars in their respective knitting sections. Consequently, a characteristic advantage of this embodiment of the invention is found in the fact that, although the welt bar carrying elements comprised within each of the multiple knitting sections of the machine are moved simultaneously and in unison throughout the length of the machine by the function of the shaft 122, common to said elements, yet such elements may be adjusted individually to suit the particular knitting section within which they are intended to function for properly moving the welt bar and accurately positioning the welt hooks.

For the purpose of rocking the shaft 120 in the direction of arrow E, to impart motion to the link devices 128 and welt bars 44, there is affixed to the shaft 120 a lever 198 having attached thereto one end of a spring 200 the other end of which is attached to a suitable portion of the machine frame. Thus it will be understood that the spring exerting a pull on the lever 198 in the direction of arrow F will cause the shaft 120 to partially rotate in the direction of arrow E, thereby exerting a pull on the link devices 128 in the direction of arrow G, accordingly withdrawing under tension the welt fabrics being knitted on the machine.

Rocking of the shaft 120 in the direction of arrow D for the purpose of moving the link devices 128 in the direction of arrow H and thus move the welt bars 44 in unison towards the needles 32, is done manually, for instance, by pushing on the arms 126, as indicated at P in Figure 3. The welt hooks 46 may be advantageously maintained in position relatively to the knitting instrumentalities during the hooking-up operation by means of a locking finger 202 manually movable for engagement with an abutment 204 suitably fixed to the shaft 120 to hold the same until relieved against the normal action of the spring 200.

In order to draw the welt fabrics from the banks of needles and maintain said fabrics under tension during the manual turning of the welt, and finally withdraw the fabrics knitted by the machine after the turning of the welts, there is provided a take-up mechanism which, as shown in Figures 13 and 14, is adaptable for associating with either form of welt bar supporting and moving mechanism. This take-up mechanism includes a shaft 206 rotatably supported in suitable bearing brackets 208 on the machine frame 20 to extend longitudinally of the machine.

Freely mounted upon the shaft 206 and held by means of collars 210 within the confines of each knitting section 28 is a pair of hollow casings 212 preferably of circular configuration and each having a bore 214 suitably formed in the peripheral surface thereof and opening therein. Received within the bore 214 of each casing 212 and rigidly connected thereto is one end 216 of a slotted tube 218 disposed so that its intermediate portion extends transversely of the front table 26 and its free end portion 220 projects towards the needle bar 30. As shown in the drawings, the intermediate portion of each slotted tube extending over the front table may be fixed thereon by means of a clamp 222.

Associated with one of the casings 212 of each pair, and fixed upon the shaft 206, for instance, by means of a lock screw 224, is a sleeve 226 having a flanged portion 228. A hub 230 is freely received on the sleeve 226 and abuts the flanged portion 228 thereof. The surface of the hub 230 abutting the flanged portion 228 of the sleeve 226 is formed with an annular recess 232 accommodating an adjustable stop 234 and a fixed stop 236 relatively disposed at diametrically opposed points on said flanged portion 228. The hub 230 is moreover provided with a pin 238 projecting into the recess 232 and adapted to contact the fixed stop 236 of the flanged portion 228 of the sleeve 226, a spring 240 being interposed between said pin and adjustable stop carried by said flanged portion.

By reason of this construction, it will be appreciated that the hub 230 is capable of torsional resiliency, which is desirable to assure the proper take-up operation, as will fully be pointed out hereinafter.

The hub 230 with its torsional resilient construction cooperates with a second hub 242 freely mounted on the shaft 206 to support a ware-roller 244 said second hub being associated with the remaining casing 212. Each hub 230 and 242 is formed with a pulley-like extension 246 enclosed in the associated casing and having a flexible cable 248 preferably in the form of a coil spring wound thereabout. One end portion 250 of each of the flexible cables 248 is fixed to the extension 246 of the corresponding hub, as shown at 252, and the other end portion 254 of each spring cable 248 passes in the associated slotted tube 218. The spring cables 248 are interconnected by means of a cross bar 256 consisting of solid end pieces 258 united to the free ends of said cables, and of an intermediate tubular piece 260 engaging said end pieces. Hooks 262 are rigidly attached to the solid end pieces 258 and engageable with welt rods 264 adapted to be laid over the welt fabrics. Each of these hooks 262 may be of a size to yieldably grip the rod 264 between the bill of the hook and its shank so as to increase the grip of the hook with the rod.

From the preceding description of the take-up mechanism, it will be understood that rotation of the shaft 206 in the direction of arrow I will wind the spring cables 248 and, accordingly, draw the hooks 262 and welt rods 264 in engagement therewith away from the needle bar 30, whereas the turning of the shaft 206 in the direction of arrow J will unwind the spring cables 248 and cause the hooks 262 to move towards the needle bar.

By reason of the spring 240 and its association with the wareroller construction, it will be understood that said spring will cooperate with the spring cables 248 to maintain the fabric under constant proper tension while affording sufficient torsional resiliency to assure free movement of the knitting needles 32 in the various functions thereof.

Rotation of the shaft 206 in the direction of arrow I which is utilized to maintain the fabric being knitted under proper tension and take up the same as knitted by the machine, is accomplished by means of a pulley or drum 266 affixed to said shaft and having a take-up cord 268 wound thereabout, said cord being maintained under constant pulling tension by passing in the well known manner over an overhead pulley and thence down to a counterweight (not shown). A handle and ratchet device 269 is shown for turning the drum 266 to wind up the cord 268 thereon

in order to provide sufficient draw-off movement by weight action.

The welt rod hooks 262 are brought into their position adjacent the needle bar 30, that is, to the position shown in dotted lines in Figure 15 of the drawings, by manually rotating the shaft 206 in the direction of arrow J.

The proper position of the hooks 262 is assured by means of a one-tooth ratchet wheel 270 on the shaft 206, to be engaged by a dog 271 pivotally supported on a suitable portion of the machine frame 20, which dog 271 may be operated in the same manner as the dog 116 hereinbefore referred to.

At this point, attention is called to the fact that the hooks 262 are maintained advantageously above the fabric and its knitting field by means of a bend 272 in the slotted tubes 218 which guides the hooks upwardly. At any time after a sufficient amount of welt fabrics have been knitted, the welt rods 264 may be brought by the operator into operative position.

To eliminate the separate manual placing of individual welt rods, an attachment for handling the welt rods on all the knitting sections is provided. As shown in the drawings, this attachment preferably comprises spring clips 274, one for each end portion of each welt rod to frictionally engage the same in the manner indicated particularly in Figure 15.

Each clip 274 is carried on a head 276 having rod guiding members 278. The heads 276 are secured to a cross bar 280 supported in arms 282 swingable over and back to operative positions, as represented in Figure 15. For that purpose, the arms 282 are mounted for swinging movement on pivots 284 in bearings 286 supported over the front table 26 of the machine frame 20 and operable to bring a series of welt rods simultaneously above the fabrics being knitted in the various knitting sections. In this manner, it will be appreciated that the welt rods are suspended over the fabrics in the path of the movement of the hooks 262 when retracted. The suspended position of the welt rods may be accurately adjusted by means of adjustable stops 288 on the arms 282 disposed to contact with the bearing supports on the machine frame.

In using the improved attachment, the initial course of loops is formed by operation of the knitting machine in the usual manner, that is, the yarn carriers 38 feed the yarn to the needles 32 which then cofunction with the sinkers and dividers 34 to form the loops which remain engaged on the needles. Following the formation of said initial course of loops, the knitting machine is stopped for permitting the welt hooks 46 on the welt bars 44 to enter between the needles 32 in line with the sinkers 34 at a point between the sinkers 34 and knockover bits 36, and subsequently receive the initial loops when cast off the sinker nibs.

The welt bars 44 which, during the knitting of the initial courses, laid in their neutral inactive position, that is, away from the needles are moved simultaneously towards the needle bars 30 and brought into operative hook-up position, that is, with the hook ends of the welt hooks 46 projecting slightly beyond the needles 32 in line with the sinkers 34 at a point between the sinkers 34 and knockover bits 36. The welt bars 44 are moved in unison towards the needle bars for the hook-up operation by manually rotating the shaft 60 or 120.

Following the hook-up, the knitting machine

11

operates in the usual manner to knit the series of courses forming the welt fabrics, which are drawn resiliently through the welt bars 44 and associated springs 86 or 160 by means of the drum 110 and take-up cable 112 or lever 198 and spring 200 functioning to rotate the shaft 60 to 120 in the direction of arrow B, which drives the welt bars away from the needles.

As the knitting of the welt proceeds, the welt rod hooks 262 are brought to their position adjacent the needle bars 30, that is, the position shown in dotted lines in Figure 15, by manually rotating the shaft 206 in the direction of arrow J. At any time after a sufficient amount of welt fabrics have been knitted, the welt rods 264 may be brought by the operator into operating position by manually rotating the shaft 284 of the welt rod supporting and positioning mechanism.

After a predetermined length of welt fabric has been knitted, the shaft 206 is rotated manually in the direction of arrow I, which resiliently retracts the hooks 262 from their position adjacent the needle bars. The hooks 262 in their retracting movement engage the associated welt rods 264, freeing the same from the spring clips 274 and, through action of the bend 272 in the slotted tube 218, draw said welt rods 264 onto the fabric.

After the knitting of the completed lengths of welt fabrics, the machine is stopped and the operator, removing the welt bars from their supports, manually turns the individual fabrics in the customary manner, after which the knitting of the remaining portions of the stocking blanks is proceeded with in the usual well known manner.

It will be understood, particularly upon reference to the diagrammatic showing in Figure 22, that all the welt bars 42 may be brought simultaneously into hook-up position by manual operation of the shaft 60, that all the welt rods 264 may be brought simultaneously into suspended position over their respective welt fabrics by manual operation of the shaft 284, and that all of said welt rods may be brought simultaneously into operative position by manual operation of the shaft 206.

In concluding, it is to be understood that the constructions herein shown and described are capable of certain modifications, without departing from the essence of the invention. Accordingly, any modifications coming within the scope of the subjoined claims are to be considered within the spirit of the invention.

What we claim is:

1. In a flat knitting machine having a plurality of knitting sections, the combination with a welt bar and a welt rod for each of said sections of: means manually operable for bringing all the welt bars simultaneously into position to engage the loops of the initial courses formed in the respective sections, and then manually operable for drawing all the welt bars simultaneously to cause their engagement with said loops; means manually operable for bringing all the welt rods simultaneously into suspended position over the fabrics being knitted; welt rod engaging devices disposed in each section; and means manually operable for bringing all of said devices simultaneously into position to engage the suspended welt rods, and then manually operable for driving said devices simultaneously into engagement with the welt rods to withdraw the latter from their suspended position and to apply the same onto the fabrics.

12

2. In a flat knitting machine having a plurality of knitting sections each provided with a bank of needles, the combination with a welt bar and a welt rod for each of said sections of: means manually operable for bringing all the welt bars simultaneously into position to engage the loops of the initial course formed in the respective sections, and then manually operable for drawing all the welt bars simultaneously to cause their engagement with said loops, said means including horizontally extending stationary rails having a predetermined fixed relationship with said banks of needles; means mechanically operable to withdraw the hooked loops and take up the fabrics being knitted in the several sections; means manually operable for bringing all the welt rods simultaneously into suspended position over said fabrics; welt rod engaging devices disposed in each section; and means manually operable for bringing all of said devices simultaneously into position to engage the suspended welt rods, and then manually operable for driving said devices simultaneously into engagement with the welt rods to withdraw the latter from their suspended position and to apply the same onto the fabrics.

3. In a flat knitting machine having a plurality of knitting sections each provided with a bank of needles, the combination with a welt bar and a welt rod for each of said sections of: means manually operable for bringing all the welt bars simultaneously into position to engage the loops of the initial courses formed in the respective sections, and then manually operable for drawing all the welt bars simultaneously to cause their engagement with said loops, said means including horizontally extending stationary rails having a predetermined fixed relationship with said banks of needles; means manually operable for bringing all the welt rods simultaneously into suspended position over the fabrics being knitted; welt rod engaging devices disposed in each section; means manually operable for bringing all of said devices simultaneously into position to engage the suspended welt rods, and then manually operable for driving said devices simultaneously into engagement with the welt rods to withdraw the latter from their suspended position and to apply the same onto the fabrics; and means mechanically operable for taking up said welt rods.

4. In a flat knitting machine having a plurality of knitting sections each provided with a bank of needles, the combination with a welt bar and a welt rod for each of said sections of: means detachably connected to the welt bars and manually operable for bringing all the welt bars simultaneously into position to engage the loops of the initial courses formed in the respective sections, and then manually operable for drawing all the welt bars simultaneously to cause their engagement with said loops, said means including horizontally extending stationary rails having a predetermined fixed relationship with said banks of needles; means mechanically operable to withdraw the hooked loops and take up the fabrics being knitted in the several sections; means manually operable for bringing all the welt rods simultaneously into suspended position over said fabrics; welt rod engaging devices disposed in each section; means manually operable for bringing all of said devices simultaneously into position to engage the suspended welt rods, and then manually operable for driving said devices simultaneously into engagement with the welt rods to

13

withdraw the latter from their suspended position and to apply the same onto the fabrics; and means mechanically operable for taking up said welt rods.

5. In a welt forming attachment for knitting machines of the character described: a welt bar; carrier devices, one for each end of the welt bar; a mechanism operable for moving said welt bar carrier devices, said mechanism including movement imparting means, lengths of flexible material establishing connections between said movement imparting means and welt bar carrier devices for pulling and pushing the latter, and rigid guide members associated with said lengths of flexible material for guiding the same in a predetermined direction in their pulling and pushing of the welt bar carrier devices; and, a welt rod operating mechanism including welt rod engaging elements, movement imparting means, flexible bands interconnecting said movement imparting means and welt rod engaging elements for advancing and retracting the latter, and rigid guide members associated with said flexible bands for guiding the same in a predetermined direction in their advancing and retracting of the welt rod engaging elements.

6. In a full-fashioned hosiery knitting machine, the combination of a welt forming mechanism, and a welt rod operating mechanism including welt rod engaging elements; movement imparting means therefor; yieldable flexible connecting means between said elements and movement imparting means; and, rigid guide members associated with said connecting means to guide the same in a predetermined path of movement.

7. In combination with a bank of knitting needles in a flat knitting machine, a welt forming attachment comprising: a welt bar; means for supporting the welt bar; movement imparting means; and means interconnecting the welt bar supporting means and the movement imparting means and including a member which is unyielding and positively moves the welt bar in one direction, and is resilient and yieldingly moves the welt bar in the opposite direction.

8. In a multi section knitting machine having welt forming mechanism, a device for laying welt rods on the fabrics in the several knitting sections comprising: a shaft extending throughout the several knitting sections and mounted for reversible rotating movements; pairs of arms fixed on said shaft to extend at right angles thereto, one pair of arms being disposed within the confines of each knitting section and each arm terminating with welt rod engaging spring means whereby, upon rotation of the shaft in one direction, the spring means of said arms may be located simultaneously in position to place the welt rod in retaining engagement therewith, and upon rotation of the shaft in the other direction, the spring means on said arms may be located simultaneously in position for releasably suspending the engaged welt rods over the fabrics being knitted in the corresponding knitting sections of the machine; and, a welt rod operating mechanism including welt rod engaging elements, movement imparting means, flexible bands interconnecting said movement imparting means and welt rod engaging elements for advancing and retracting the latter, and rigid guide members associated with said flexible bands for guiding the same in a predetermined direction in their advancing and retracting of the welt rod engaging elements.

9. In a multi section knitting machine having

14

welt forming mechanism, a device for laying welt rods on the fabrics in the several knitting sections comprising: welt rod retaining spring means within each knitting section adapted to engage the welt rod for use therein and movable to operative position for suspending said welt rod over the corresponding fabric; supporting and positioning means for said welt rod retaining spring means and including a member extending throughout the several knitting sections for moving all of said welt rod retaining spring means simultaneously to operative position; and, a welt rod operating mechanism including welt rod engaging elements, movement imparting means, flexible bands interconnecting said movement imparting means and welt rod engaging elements for advancing and retracting the latter, and rigid guide members associated with said flexible bands for guiding the same in a predetermined direction in their advancing and retracting of the welt rod engaging elements.

10. In combination with a welt attachment for knitting machines of the character described, a fabric take-up comprising: a welt rod operating mechanism including welt rod engaging elements; movement imparting means; yieldable flexible connecting cables between said movement imparting means and welt rod engaging elements for advancing and retracting the latter; and rigid guide members associated with said connecting cables for guiding the same in a predetermined direction in their advancing and retracting of the welt rod engaging elements.

11. In combination with a welt attachment for knitting machines of the character described, a fabric take-up comprising: a welt rod operating mechanism including welt rod engaging elements; movement imparting means; coil springs interconnecting said movement imparting means and welt rod engaging elements for advancing and retracting the latter; and rigid guide members associated with said coil springs for guiding the same in a predetermined direction in their advancing and retreating of the welt rod engaging elements.

12. A fabric take-up for knitting machines of the character described comprising: a welt rod operating mechanism including welt rod engaging elements; movement imparting means; yieldable flexible connecting cables between said movement imparting means and welt rod engaging elements for advancing and retracting the latter; and rigid guide members associated with said connecting cables for guiding the same in a predetermined direction in their advancing and retracting of the welt rod engaging elements.

13. In a flat knitting machine, a fabric take-up mechanism comprising in combination with a welt rod: a welt rod operating mechanism including welt rod engaging elements; movement imparting means therefor; yieldable flexible connecting means between said elements and movement imparting means; and rigid guide members associated with said connecting means to guide the same in a predetermined path of movement.

14. A combined welt turning and take-up attachment for flat knitting machines comprising, in combination with a welt bar and a welt rod: a welt bar mechanism and a welt rod mechanism; said welt bar mechanism including a carrier device for each end of the welt bar, and movement imparting means having a take-up shaft and yieldable means attached to the take-up shaft and connected to said carrier devices; said welt rod mechanism including a welt rod engaging ele-

75

ment for each end of the welt rod, and movement imparting means having a wareroller shaft and yieldable means attached to the wareroller shaft and connected to said welt rod engaging elements.

15. A combined welt turning and take-up attachment for flat knitting machines comprising, in combination with a welt bar and a welt rod: a welt bar mechanism and a welt rod mechanism; said welt bar mechanism including a carrier device for each end of the welt bar, and movement imparting means having a take-up shaft and yieldable means in the form of coil springs attached at one end to the take-up shaft and connected to the carrier devices; said welt rod mechanism including a welt rod engaging element for each end of the welt rod, movement imparting means having a wareroller shaft and yieldable means in the form of coil springs attached at one end to the wareroller shaft and connected at the other end to said welt rod engaging elements.

16. In a flat knitting machine having a needle bar, a welt forming attachment comprising: a welt bar; a mechanism including an oscillating device operable to impart movements to said welt bar; and a means connecting the welt bar to said mechanism, said means including a rigid hollow member, a connection piece slidably mounted in one end of said hollow member and connected to the welt bar, a connection element including a slideable part mounted in the other end of said hollow member and connected to said device, and a coil spring enclosed in said hollow member and interconnecting said piece and element for relative yieldable sliding movement with respect to the rigid hollow member.

17. In a flat knitting machine having a needle bar, a welt forming attachment comprising: a welt bar; a mechanism including an oscillating device operable to impart movements to said welt bar; and a means connecting the welt bar to said mechanism, said means including a rigid hollow member, a connection piece slidably mounted in one end of said hollow member and connected to the welt bar, a connection element including a slideable part mounted in the other end of said hollow member and having means for establishing a detachable connection with said device, and a coil spring enclosed in said hollow member and interconnecting said piece and element for relative yieldable sliding movement with respect to the rigid hollow member.

18. In combination with a bank of knitting needles in a flat knitting machine, a welt forming attachment comprising: a welt bar; means for imparting movements to said welt bar in relation to the knitting needles; and means adjustable universally for guiding the welt bar in a predetermined, regulatable path with respect to said needles.

19. In combination with a bank of knitting needles in a flat knitting machine, a welt forming attachment comprising: a welt bar movable towards and in relation to the needles; means for guiding the welt bar in its movement; and means for adjusting said welt bar guiding means lengthwise, crosswise, and sidewise with respect to the needles.

20. In a flat knitting machine having a needle bar, a welt forming attachment comprising: a welt bar; a mechanism including an oscillating lever operable to impart movements to said welt bar; and a linking device connecting the welt bar to said mechanism, said device including a rigid

hollow member, a connection piece slidably mounted in one end of said hollow member and connected to the welt bar, a connection element slidably mounted in the other end of said hollow member and connected to said lever, and a coil spring enclosed in said hollow member and interconnecting said piece and element for relative yieldable sliding movement with respect to the rigid hollow member.

10 21. In a flat knitting machine having a needle bar, a welt forming attachment comprising: a welt bar; a mechanism including an oscillating lever operable to impart movements to said welt bar; and a linking device connecting the welt bar to said mechanism, said device including a rigid hollow member, a connection piece slidably mounted in one end of said hollow member and connected to the welt bar, a connection element slidably mounted in the other end of said hollow member and having means for establishing a detachable connection with said lever, and a coil spring enclosed in said hollow member and interconnecting said piece and element for relative yieldable sliding movement with respect to the rigid hollow member.

15 22. In combination with a bank of knitting needles in a flat knitting machine, a welt forming attachment comprising: a welt bar; means for imparting welt turning movements to said welt bar in relation to the knitting needles; and means adjustable universally for guiding the welt bar in a predetermined, regulatable path with respect to said needles.

20 23. In combination with a bank of knitting needles in a flat knitting machine, a welt forming attachment comprising: a welt bar movable towards and in relation to the needles for turning and forming a welt; means for guiding the welt bar in its movement; and means for adjusting said welt bar guiding means lengthwise, crosswise, and sidewise with respect to the needles.

25 24. In a flat knitting machine having a plurality of knitting sections, each provided with a bank of needles, the combination with a welt bar and a welt rod for each of said sections of: means manually operable for bringing all the welt bars simultaneously into position to engage the loops of the initial courses formed in the respective sections, and then manually operable for drawing all the welt bars simultaneously to cause their engagement with said loops, said means including horizontally extending stationary rails having a predetermined fixed relationship with said banks of needles; carrier devices 30 slidably mounted on said rails and detachably supporting the welt bars; means manually operable for bringing all the welt rods simultaneously into suspended position over the fabrics being knitted; welt rod engaging devices disposed in each section; and means manually operable for bringing all of said devices simultaneously into position to engage the suspended welt rods, and then manually operable for driving said devices simultaneously into engagement with the welt rods to withdraw the latter from their suspended position and to apply the same onto the fabrics.

35 25. In a full-fashioned hosiery knitting machine, in combination: a shaft; a wareroller rotatably mounted on said shaft; a yieldable connection between said roller and shaft; a welt rod; and mechanism for operating the welt rod including a pair of cables each having an end portion attached to said wareroller.

40 26. In a full-fashioned hosiery knitting machine, in combination: a shaft; a wareroller ro-

75

tatably mounted on said shaft; a yieldable connection between said roller and shaft; a welt rod; mechanism for operating the welt rod including a pair of flexible cables each having an end portion wrapped about and attached to said wareroller; and supporting and guiding means for said cables, whereby said mechanism is guided into engagement with the welt rod.

27. In a full-fashioned hosiery knitting machine, in combination: a welt rod; means for operating the welt rod including a coil spring provided with a hook for engagement with the welt rod; and guide means for the coil spring whereby the coil spring is guided in its movement for bringing about engagement of the hook with the welt rod.

28. In a full-fashioned hosiery knitting machine, in combination: a shaft; a wareroller rotatably mounted on said shaft; a yieldable connection between said roller and shaft; a welt rod; mechanism for operating the welt rod including a pair of cables each having an end portion attached to said wareroller; a welt bar; a second shaft having a wareroller thereon; and mechanism for operating said welt bar including a pair of cables each having an end attached to the wareroller of said second shaft.

29. In a full-fashioned hosiery knitting machine including a bank of needles, in combination: a shaft; a wareroller rotatably mounted on said shaft; a yieldable connection between said roller and shaft; a welt rod; mechanism for operating the welt rod including a pair of cables each having an end portion coiled about said wareroller; means supporting said cables for movements towards and away from said needles; a welt bar; a second shaft having a wareroller thereon; mechanism for operating said welt bar including a pair of cables each having an end attached to the wareroller of said second shaft; and a welt rod supporting device associated with the welt rod operating mechanism whereby a welt rod may be supported and moved into contact with the knitted fabric and into position to be engaged by said welt rod operating mechanism.

30. In a full-fashioned hosiery knitting machine, in combination: a shaft; a wareroller rotatably mounted on said shaft; a yieldable connection between said roller and shaft; a welt rod; mechanism for operating the welt rod including a pair of coil springs each having an end portion attached to said wareroller; a welt bar; a second shaft having a wareroller thereon; mechanism for operating said welt bar including a pair of coil springs each having an end attached to the wareroller of said second shaft; and a welt rod supporting device associated with the welt rod operating mechanism whereby a welt rod may be supported and moved into contact with the knitted fabric and into position to be engaged by said welt rod operating mechanism.

31. A welt bar and welt rod operating attachment for flat knitting machines comprising, in combination: carrier devices, one for each end of the welt bar; a mechanism operable for operating the welt bar including movement imparting means; yieldable flexible connecting cables between said means and said devices for pulling and pushing the latter; rigid guide members associated with said cables for guiding the same in their pulling and pushing of said devices; a welt rod operating mechanism including a fabric draw-off member for attachment to the welt rod; and

means to move said member in a direction opposite to that of its draw-off movement.

32. A welt bar and welt rod operating attachment for flat knitting machines comprising, in combination: carrier devices, one for each end of the welt bar; a mechanism operable for operating the welt bar including movement imparting means; coil springs between said means and said devices for pulling and pushing the latter; rigid guide members associated with said coil springs for guiding the same in their pulling and pushing of said devices; a welt rod operating mechanism including a fabric draw-off member for attachment to the welt rod; and means to move said member in a direction opposite to that of its draw-off movement.

33. A welt bar and welt rod operating attachment for a knitting machine, comprising: a pair of rotatable shafts; coil springs providing operative connections between said shafts and the welt bar and welt rod; and means associated with said coil springs whereby rotation of said shafts in opposite directions will push or pull the welt bar and draw and tension the welt rod.

34. A welt bar and welt rod operating attachment for a knitting machine, comprising: a pair of rotatable shafts; means providing an operative connection between the welt bar and one of said shafts whereby rotation of the shaft in opposite directions will pull or push the welt bar; and resilient means providing an operative connection between the welt rod and the other of said shafts whereby rotation of the shaft in one direction engages said second means with the welt rod, and rotation of the shaft in the opposite direction will draw and tension the welt rod.

35. A welt bar and welt rod operating attachment for a knitting machine, comprising: a pair of rotatable shafts; means providing an operative connection between the welt bar and one of said shafts whereby rotation of the shaft in opposite directions will pull or push the welt bar; resilient means providing an operative connection between the welt rod and the other of said shafts whereby rotation of the shaft in opposite directions will connect said second means with the welt rod and draw and tension the same; a pulley on each shaft; and weighted cables wrapped around said pulleys whereby the shafts may be turned in one direction on the unwrapping of the cables from the pulleys.

36. A welt bar operating mechanism for flat knitting machines having a bank of needles, comprising: a support for the bar, and means connected to the support for moving the bar towards and away from the bank of needles and resiliently tension the fabric as knitted and including a shaft, a pulley on the shaft, and a weighted cable connected to the pulley.

37. A welt bar operating attachment for flat knitting machines having a bank of needles, comprising: a pair of rails positioned relative to the needles; a support for the welt bar movable on the rails towards and away from the needles; a shaft; a roller on said shaft; resilient stretchable elements wrapped around said roller and connected to said support during its movement towards or away from the bank of needles; a pulley on said shaft; and a weighted cable wrapped around said pulley to tension the shaft.

38. In a flat knitting machine having multi knitting sections including banks of needles, an attachment therefor comprising, in combination: a welt bar for each section; a welt rod for each section; means for resiliently moving simultane-

ously all the welt bars towards and away from the banks of needles; a weighted cable for tensioning said means; means for simultaneously placing all of the welt rods upon the fabrics being knitted; means for simultaneously engaging all the welt rods and resiliently moving the same to tension the fabrics as knitted; and a weighted cable for tensioning said third means.

39. A welt bar and welt rod operating attachment for a flat knitting machine having a bank of needles comprising, in combination: a mechanism for moving the welt bar towards and away from the needles and a mechanism for engaging and moving the welt rod relative to the needles; said welt bar mechanism consisting of a pair of slidably mounted plates for supporting the welt bar, a rotatable shaft, a pair of casings rotatably mounted on said shaft, a pair of clutch devices secured to said shaft and including movably mounted plungers for engagement and disengagement with said casings, a pair of channel rails extending from and communicating with the interior of said casings and slidably supporting said plates, and a pair of flexible cables supported by said rails and each coiled within a casing and having one end secured to a casing and the other end secured to one of said plates; and said welt rod mechanism consisting of a rotatable shaft, a pair of casings rotatably mounted on said shaft, a sleeve fixed to said shaft, a wareroller rotatably mounted on said shaft and having its end portions housed within said casings, slotted tubes extending from and communicating with the interior of said casings, welt rod engaging hooks, and flexible cables mounted in said tubes and coiled about said wareroller and housed within said casings and each having one end attached to the wareroller and the other end attached to the welt rod engaging hooks.

40. A welt bar and welt rod operating attachment for a flat knitting machine having a bank of needles comprising, in combination: a mechanism for moving the welt bar towards and away from the needles and a mechanism for engaging and moving the welt rod relative to the needles; said welt bar mechanism consisting of a pair of slidably mounted plates for supporting the welt bar, a rotatable shaft, a pair of casings rotatably mounted on said shaft, a pair of clutch devices secured to said shaft and including movably mounted plungers for engagement and disengagement with said casings, a pair of channel rails extending from and communicating with the interior of said casings, and slidably supporting said plates, and a pair of coil springs slidably supported by said rails and each coiled within a casing and having one end secured to a

5

casing and the other end secured to one of said plates; and said welt rod mechanism consisting of a rotatable shaft, a pair of casings rotatably mounted on said shaft, a sleeve fixed to said shaft, a wareroller rotatably mounted on said shaft and having its end portions housed within said casings, slotted tubes extending from and communicating with the interior of said casings, welt rod engaging hooks, and coil springs slidably mounted in said tubes and coiled about said wareroller and housed within said casings and each having one end attachment to the wareroller and the other end attached to the welt rod engaging hooks.

10

41. A welt bar and welt rod operating and supporting attachment for a flat knitting machine having a bank of needles comprising, in combinations:

a mechanism for operating the welt bar towards and away from the needles, a mechanism for engaging and operating the welt rod relative to the needles, and a device for supporting the welt rod in a position to be engaged by the welt rod operating mechanism; said welt bar mechanism consisting of a pair of slidably mounted plates for supporting the welt bar, a rotatable shaft, a pair of casings rotatably mounted on said shaft, a pair of clutch devices secured to said shaft and including movably mounted plungers for engagement and disengagement with said casings, a pair of channel rails extending from and communicating with the interior of said casings and slidably supporting said plates, and a pair of coil springs supported by said rails and each coiled within a casing and having one end secured to a casing and the other end secured to one of said plates; said welt rod mechanism consisting of a rotatable shaft, a pair of casings rotatably mounted on said shaft, a sleeve fixed to said shaft, a wareroller rotatably mounted on said shaft and having its end portions housed within said casings, slotted tubes extending from and communicating with the interior of said casings, welt rod engaging hooks, and coil springs mounted in said tubes and coiled about said wareroller and housed within said casings and each having one end attached to the wareroller and the other end attached to the welt rod engaging hooks; and said welt rod supporting device consisting of a pair of pivotally mounted arms, a cross bar connecting the arms together, a pair of heads mounted on said cross bar, and spring clips carried by said heads and adapted to removably support the welt rod in the path of movement of said welt rod engaging hooks.
